US0D1104977S

(12) **United States Design Patent** (10) **Patent No.:** **US D1,104,977 S**
(45) **Date of Patent:** **** Dec. 9, 2025**

(54) **ELECTRICAL CONNECTOR**

(71) **Applicant:** **UC UniK Technology Ltd.**, New Taipei (TW)
(72) **Inventor:** **Teng-Yong Wang**, New Taipei (TW)
(73) **Assignee:** **UC UNIK TECHNOLOGY LTD.**, New Taipei (TW)

(**) **Term:** **15 Years**

(21) **Appl. No.:** **29/970,984**

(22) **Filed:** **Oct. 31, 2024**

(51) **LOC (15) Cl.** 13-02
(52) **U.S. Cl.** USPC D13/120

(57) **CLAIM**

The ornamental design for an electrical connector as shown and described.

DESCRIPTION

FIG. 1 is a front, right-side and top perspective view of a first embodiment of an electrical connector showing my new design;

FIG. 2 is a front, right-side and bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front, right-side and top perspective view of a second embodiment of the electrical connector;

FIG. 10 is a front, right-side and bottom perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof; and,

FIG. 16 is a bottom plan view thereof.

The dashed broken lines depict portions of the electrical connector that form no part of the claimed design.
